(57) **CLAIM**

I claim, the ornamental design for a lamp refractor, as shown and described.

DESCRIPTION

FIG. 1 is a front perspective view of a lamp refractor, showing my new design;

FIG. 2 is a front elevation view thereof;

FIG. 3 is a side elevation view taken from the left of FIG. 2;

FIG. 4 is a side elevation view taken from the right of FIG. 2;

FIG. 5 is rear elevation view thereof;

FIG. 6 is a top plan view thereof; and,

FIG. 7 is a bottom plan view thereof.

The broken lines illustrating portions of the lamp refractor form no part of the claimed design.

1 Claim, 5 Drawing Sheets
